MACHINE FOR PRODUCING CELLULOSE SHEETS AND THE LIKE

Emil Czapek, New York, N. Y.

Original application August 12, 1937, Serial No. 158,747. Divided and this application August 3, 1940, Serial No. 350,290

13 Claims. (Cl. 18—15)

This invention relates to devices for producing improved cellulose sheets, films or the like, and the present application constitutes a division of my co-pending application Serial No. 158,747 filed August 12, 1937.

Among the objects of the present invention, it is aimed to provide devices for producing an improved cellulose sheet, film or the like of an exceedingly uniform physical structure throughout having a practically equal tension and shrinkage characteristic in length as well as in width.

It is still another object of the present invention to provide devices for producing an improved cellulose sheet, film or the like of an exceedingly slight thickness as an instance having a weight per one thousand square inches of less than 0.40 ounce without striations and the like and having a width of forty inches or more by means of a continuously operating process.

It is still another object of the present invention to provide devices for producing an improved cellulose sheet, film or the like of unusual thickness with an exceedingly uniform physical structure throughout.

It is still another object of the present invention to provide devices for carrying out improved processes for producing the aforesaid improved cellulose sheets, films and the like.

These and other features, capabilities and advantages of the invention will appear from the subjoined detail description of specific embodiments thereof illustrated in the accompanying drawings in which

Figure 1 is a section of one embodiment more or less diagrammatically shown;

Fig. 2 is a section of another embodiment more or less diagrammatically shown;

Fig. 3 is a fragmental end elevation of a stripping device used in these embodiments; and

Fig. 4 is a fragmental section of the stripping device shown in Fig. 3.

To carry out this invention, a pouring base is used upon which a cellulose solution in the form of a layer is spread. The layer becomes solidified as the result of immersing the base into a coagulation liquid.

The essential novelty and the advancement achieved resides in the fact that not only is the coagulation of the layer carried out on the base but part of the subsequent regeneration of the coagulated strip is also so carried out on the base and, at least, long enough so that the strip will become sufficiently solidified so that it cannot be stretched and deformed thereafter.

A further innovation of this invention resides in the provision of a device which enables introducing a coagulation solution under the strip and to wet the base during the process to aid in the regeneration reaction.

In the process carried out by the present devices, a thick liquid 1 of cellulose solution, for instance viscose, is spread upon the surface 2 of a pouring base 3 by means of a pouring device 4. By moving or rotating the pouring base 3 the so spread cellulose layer 5 passes into a suitable coagulation liquid 6 provided in the container or trough 7.

The character of the liquid 6 depends upon the cellulose solution being used. For viscose a sulphuric acid bath with a supplementary agent of sodium, ammonia or a similar sulphate is chosen as the coagulation and regeneration liquid. The strength of the solution must be chosen to correspond to the effect desired as is hereinafter set forth.

In accordance with the present invention, the coagulation of the layer 5 starts while the layer passes the point 8 on the surface 2 where the layer 5 on the base enters the coagulation bath. The velocity of the movement of the base 3 and the concentration of the liquid 6 is of such a character, that the coagulation is completed before it passes the point indicated as 9 in Fig. 1.

After the layer 5 is coagulated to a strip which is still soft and delicate, the regeneration of the strip and its solidification begins. After this coagulation has so taken place, the coagulation liquid 6 starts wetting the surface 2 which was dry until now by diffusing through the strip 5.

The start of the regeneration process is aided by passing fresh coagulation solution onto the lower side of the strip 5 between the strip 5 and the surface 2 by means of the stripping device 10 which will hereinafter be set forth in detail. This device 10 takes the place of the surface 2 for a short time as the strip 5 slides over it while the device 10 moistens the lower side of the strip 5 as well as the surface 2 of the base 3 during this short period.

Beyond the device 10, the strip again passes onto the surface 2 and while so spread on it may thus be moistened with a fresh coagulation fluid and regenerated without being stretched, extended or shrunk.

The device 10 while not necessarily positioned above the level of the bath 6 is so illustrated in Fig. 1 as exemplifying one embodiment of the invention, but at least should be positioned at

a point where the coagulation fluid begins to penetrate the strip or layer 5 to the surface 2.

If necessary, the roller 11, as shown in Fig. 2, may be provided to guide the strip 5 as it passes from the device 10 back to the surface 2.

The strip 5 which by now should be coagulated sufficiently so that it cannot be deformed any more, is then removed with the aid of the roller 12. As the surface 2 has been moistened with coagulation fluid at least at the point 9, and fresh coagulation fluid supplied to the surface 2, the removal of the strip 5 at the roller 12 will take place very easily and safely, particularly as compared to the processes heretofore known. Consequently, there is no danger of the strip sticking to the surface 2 nor in being impaired or injured when being removed from the surface 2.

The moisture which remains on the surface 2 after the removal of the strip, is wiped off by scraping means, such as the pivotally mounted scrapers 13 so that the surface 2 will be dry again after passing such scrapers 13. As a special precaution effectively to dry this surface 2, before returning to the nozzle 4, the remaining moisture, if any, may be wiped off or evaporated by warm air supplied by the blower 14.

After the strip 5 is removed by the roller 12, it is passed through different treatment baths, washed and the like and finally dried. The device 10 shown in Figs. 3 and 4 comprises a main body 21 which is pivotally mounted on the shaft 22 or the like. At the end of this main body 21 which is removed from its pivotal point 22, there is provided a flexible blade 24 preferably composed of metal which is placed in a slit 23 in the present instance and secured by screws 25. The blade 24 is mounted to press against the surface 2 and is ground in such a way that it lies in intimate engagement with the surface 2 throughout its whole width.

Transversely through the main body 21, there extends the supply chamber 26 which forms a channel to receive the coagulation liquid supplied thereto by any suitable means such as a pump or the like.

This chamber 26 may be used to supply any other liquid between the strip 5 and the surface 2. The quantity of the liquid so supplied will of course be controlled by the pump (not shown).

A large number of minute orifices such as 27, 28 and 29 are provided to form communications between the chamber 26 and the inner or lower surface of the strip 5, the surface 2 and even the blade 24.

The device 10 preferably also is tapered at its end adjacent to its shaft 22 as shown and provided with a slit 30 and screws 31 to receive and secure the blade 32 preferably composed of rubber which intimately engages the surface 2.

The blade 24, which constitutes the advance edge relative to the movement of the pouring base 3 effects the transfer of the strip 5 from the surface 2 to the back of the device 10. The supply of liquid through the orifices 27 and 29 facilitates the transfer of the strip 5 onto the back of the device 10. The blade 32 guides the strip 5 back to the surface 2, so that throughout this path of movement the strip 5 is constantly supported, so that it may not acquire any striations, streaks or irregularities.

The strip 5 while so advanced on the back of the device 10, the surface 2 is supplied with liquid through the orifices 28 and thereby moistened.

The mode of operation of the process made

possible with these devices comprises completing not only the coagulation upon the surface 2 but also the subsequent reactions, for the period required completely to solidify the strip 5. During the main coagulation reaction, the pouring base 3 is dry but thereafter and that is just before arriving at the device 10 and the covered part beyond it, the pouring base 3 is moistened with coagulation fluid or with a similar suitable liquid. This process is particularly characterized by providing the device 10 which supplies a fresh reaction liquid between the strip 5 and the surface 2 and insures that the strip 5 at this time is not transported without an effective support and furthermore in that between the removing roller 12 and the pouring base 3, the surface 2 is freed of moisture and arrives in a dry condition at, and under the nozzle 4.

In the embodiment shown in Fig. 1, the device 10 is located above the level of the coagulation fluid 6, the guiding roller 11 of Fig. 2 dispensed with and the strip 5 preferably removed by the conveyor 33 extending around the rollers 34 and 35, the roller 35 being disposed above the trough 36 into which the strip 5 is then advanced, from which the strip 5 is fed by any suitable means to one or more or other treatment baths and the like according to the process being practiced.

In the embodiment shown in Fig. 2, on the other hand, after the strip 5 is removed by the roller 12, it passes under the idler 37 and then over the roller 38 whereupon it is advanced down into the trough 39.

Preferably especially when the device 10 is positioned below the level of the liquid 6, in order to insure maintaining the stripping blade 24 in intimate engagement with the surface 2 of the base 3, the shaft 22 has fixed thereon a lever 40 to receive the weight 41 as shown to exercise a torque on the shaft 22 and in turn to press the blade 24 into intimate engagement with the surface 2 of the base 3 as shown.

It is obvious that various changes and modifications may be made to the details of construction without departing from the general spirit of the invention as set forth in the appended claims.

What I claim is:

1. The combination of a supporting base, a feed having its discharge end disposed adjacent to the base for pouring in the form of a layer of viscose and the like cellulose solutions directly onto the base without passing through any unsupported intervening free space, a coagulating bath, means for actuating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base after completing the freeing action.

2. The combination of a rotatable supporting base, a feed having its discharge end disposed adjacent to the base for pouring in the form of a layer of viscose and the like cellulose solutions directly onto the base without passing through any unsupported intervening free space, a coagulating bath, means for rotating said base through said coagulating bath until the coagulating fluid

of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base after completing the freeing action.

3. The combination of a supporting base, a feed having its discharge end disposed adjacent to the base for pouring in the form of a layer of viscose and the like cellulose solutions directly onto the base without passing through any unsupported intervening free space, a coagulating bath, means for actuating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base after completing the freeing action, and having a coagulation fluid supply chamber, and having orifices communicating with said supporting base and the inner face of said layer to supply coagulation fluid thereto during the freeing action.

4. The combination of a rotatable supporting base, a feed having its discharge end disposed adjacent to the base for pouring in the form of a layer of viscose and the like cellulose solutions directly onto the base without passing through any unsupported intervening free space, a coagulating bath, means for rotating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base after completing the freeing action, and a stripping device for stripping the layer from said base after the coagulation has been fully effected.

5. The combination of a rotatable supporting base, a feed having its discharge end disposed adjacent to the base for pouring in the form of a layer of viscose and the like cellulose solutions directly onto the base without passing through any unsupported intervening free space, a coagulating bath, means for rotating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface

associated with said device for detaching and returning the film layer to the base after completing the freeing action, a stripping device for stripping the layer from said base after the coagulation has been fully effected, and scrapers for freeing the base of any coagulation fluid deposits after the layer has been stripped.

6. The combination of a rotatable supporting base, a feed having its discharge end disposed adjacent to the base for pouring in the form of a layer of viscose and the like cellulose solutions directly onto the base without passing through any unsupported intervening free space, a coagulating bath, means for rotating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base after completing the freeing action, a stripping device for stripping the layer from said base after the coagulation has been fully effected, scrapers for freeing the base of any coagulation fluid deposits after the layer has been stripped, and a blower for directing a warm blast of air onto the base so freed from any coagulation fluid deposits so that the face of the base presented to the feed will always be dry.

7. The combination of a rotatable supporting base, a feed having its discharge end disposed adjacent to the base for pouring in the form of a layer of viscose and the like cellulose solutions directly onto the base without passing through any unsupported intervening free space, a coagulating bath, means for rotating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and being tapered at both edges of said surface, and guiding blades associated with said edges to guide the film layer from the supporting base, over said device, and back onto the supporting base.

8. The combination of a supporting base, a feed having its discharge end disposed adjacent to the base for pouring in the form of a layer of viscose and the like cellulose solutions directly onto the base without passing through any unsupported intervening free space, a coagulating bath, means for actuating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base after completing

the freeing action, said device being disposed above the level of said coagulating bath.

9. The combination of a supporting base, a feed having its discharge end disposed adjacent to the base for pouring in the form of a layer of viscose and the like cellulose solutions directly onto the base without passing through any unsupported intervening free space, a coagulating bath, means for actuating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base after completing the freeing action, said device being disposed below the level of said coagulating bath.

10. The combination of a supporting base, a feed having its discharge end disposed adjacent to the base for pouring in the form of a layer of viscose and the like cellulose solutions directly onto the base without passing through any unsupported intervening free space, a coagulating bath, means for actuating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base after completing the freeing action, and a weighted arm for maintaining the advance edge of said device in intimate engagement with said supporting base.

11. The combination of a rotatable supporting base, a feed having its discharge end disposed adjacent to the base for pouring in the form of a layer of viscose and the like cellulose solutions directly onto the base without passing through any unsupported intervening free space, a coagulating bath, means for rotating said base through said coagulating bath until the coagulating fluid of the bath has started penetrating

5 to the supporting base thereby to moisten the same, a device for freeing the formed film layer from the supporting base, continuing to support the film layer during the freeing action, and returning the layer to said base after completing the freeing action, said device including a supporting surface for the film during the freeing action and being tapered at its advance edge, and a guiding blade secured to said tapered edge and forming a continuation of said tapered advance edge extending between said supporting base and the supported film layer.

12. The combination of a supporting base, a feed for pouring in the form of a layer of viscose and the like cellulose solutions onto the base, a coagulating bath, means for actuating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base, one of which guides serves as a stripper to free the film from the supporting base and the other of which guides serve to return the layer to the supporting base after leaving the device.

13. The combination of a supporting base, a feed for pouring in the form of a layer of viscose and the like cellulose solutions onto the base, a coagulating bath, means for actuating said base through said coagulating bath until the coagulating fluid of the bath has started penetrating to the supporting base thereby to moisten the same, a device for freeing the formed film layer from the supporting base, continuing to support the film layer during the freeing action, and returning the layer to said base after completing the freeing action, said device including a supporting surface for the film during the freeing action and guides at both ends of said surface associated with said device for detaching and returning the film layer to the base, a coagulation fluid supply chamber in said device, and apertures in said device extending from the chamber to the guides to supply coagulation fluid thereto during the freeing action.

EMIL CZAPEK.
